UNITED STATES PATENT OFFICE

2,000,204

VIBRATORY CURRENT INTERRUPTER

Willis A. Whipple, Chicago, Ill.

Application January 28, 1932, Serial No. 589,410

2 Claims. (Cl. 200—90)

My invention relates to means whereby uniform control and regulation of the current in a high frequency generator is provided; the invention being more especially intended for use with a high frequency generator, employing vacuum electrodes, adapted for electro-therapeutic purposes and generally known as a high frequency generator or violet ray outfit.

My invention pertains more particularly to the construction of the interrupting or regulating mechanism and to the method of mounting the same so as to provide a uniform regulation and at the same time provide for the safe use of the apparatus by eliminating all possibility of causing a shock to the user of the apparatus.

The objects and advantages of my invention will be more readily comprehended from the detailed description of the accompanying drawing, wherein:

Figure 1 is a side elevation of my improved interrupter or regulating mechanism designed for use with a high frequency generator or violet ray apparatus; a portion of the housing being shown in section.

Figure 2 is an elevation as viewed substantially at right angles to Figure 1, with housing omitted.

Figure 3 is a vertical sectional view taken substantially along the line 3—3 of Figure 2 as viewed by the arrows.

Figure 4 is a cross-sectional view taken on the line 4—4 of Figure 2, looking downwardly.

As previously stated, my invention relates to control means intended more particularly for electro-therapeutic apparatus involving high frequency coils which are mounted in a suitable housing, a portion of which is shown at A in Figure 1. The housing or shell is made of non-conducting material and generally of tubular shape to enable the same to be easily held by the user; the control mechanism, which involves my invention, being secured at one end of the housing, while the opposite end (not shown) is provided with a socket arranged to receive the well known types of vacuum electrodes adapted to be applied to the body of the user.

The housing is provided with the well known type of resonator coil and magnet coil insulatedly arranged at predetermined distances apart within the housing; but as the coils and their arrangements form no part of my invention illustration thereof has not been made and therefore detailed description of these elements need not be entered into.

My improved vibratory current interrupter is preferably intended to be mounted in one end of the housing adjacent to the end of one of the suitably encased or wrapped coils. This coil, which is usually suitably secured to an insulating plate or disc 10, has its metallic core, of which a portion is shown at 11, disposed through the

disc 10 and slightly to the opposite side in order to permit the vibrator element 12 to make contact therewith.

The vibrator element 12, comprising a suitable metallic annular plate or disc, is mounted on the free end of a leaf spring 13, whose downwardly bent end 14 is secured on the insulating disc or plate 10, as shown in Figures 1 and 4.

The element 12 is provided with an upstanding stud or contact point 15, shown disposed centrally above the element 12 and the coil core 11; the spring 13 normally tending to yieldingly hold the element 12 in slight spaced relation with the coil-core 11 as shown.

Mounted on the insulating plate or disc 10 is a resilient plate or leaf spring 16, disposed transversely of the disc and over the contact point 15; the ends of the spring 16 being bowed as shown at 17, 18 and thence disposed in a vertical direction downwardly as at 19, 20, and these ends 20 suitably secured on the insulating disc 10, as at 18.

The main transverse portion of the spring 16 on its lower face is centrally provided with a contact element or point 20. The element 20, like element 15, is provided with a flat contact forming face or end; and this element 20 is normally held in slight spaced relation with contact element or point 15 by the action of spring plate 16, as shown in Figure 3.

As is apparent from the construction, spring 16 is adapted to flex downwardly as indicated in Figure 1, for the desired current flow into the vacuum electrodes of the apparatus; the strength of the current being controlled or regulated by the adjustable relation between the contact elements or points 20 and 15 and the coil core 11.

That is to say, when the spring 16 is in normal non-flexed condition and the contact element or point 20 held in its maximum spaced relation as shown in Figure 3, the circuit between contact element or point 15 and point 20 is open, at which time contact point 15 is also in maximum spaced relation with the core 11 of the upper coil in the housing, thus affecting current flow into the vacuum electrode at the opposite end of the holder or housing; the flow of current being effected and its strength regulated by the regulated relation between contact elements or points 20 and 15 and the relation of the latter to the core 11.

The insulating plate or disc 10 is shown provided with a pair of upright posts 21, 21, suitably secured thereto and disposed upwardly above the plane of the spring member 16.

The upper ends of the posts 21, 21 support a transversely disposed plate or bar 22, which is provided with an internally threaded sleeve 23 rigidly secured, in any suitable manner, against movement.

The transversely disposed plate or bar 22 is intended to be secured on the inner face of the end wall *a* of the housing or shell *A*; the end wall *a* having an opening to permit the regulating screw (later described) to extend therethrough.

5 The sleeve 23 is provided with an adjusting screw or regulator 24.

The lower end of regulator 24 is preferably provided with a serrated or toothed annular head 10 or disc portion 25; while the upper end of the adjusting screw or regulator 24 (disposed through the end wall of the housing) is provided with a suitable finger grasping button or knob 26, preferably composed of suitable non-conducting material. The knob 26 is preferably threaded on 15 the screw 24 so as to permit assembly of the parts.

The lower end of the adjusting screw 24 is centrally bored to receive the reduced shank of a fibre or non-conducting stud 27, which is intended 20 to control the spring member 16, as shown in Figure 1.

In order to maintain the regulator 24 and hold it against accidental rotation, I provide a spring 25 detent 28; one end whereof is immovably secured to one of the posts 21, while the free end 20 is formed to frictionally bear against and engage between the serrations or teeth of member 25.

The device, of course, is provided with a suitable cord or wire (preferably disposed through 30 the end wall of the housing) for conducting current to the coils and the spring members 13 and 16 are each electrically connected with the coils within the housing of the device, so that both contact members or points 15 and 20 are electrically charged when the current supply cord or wire of the device is plugged into a suitable 35 socket or switch. In devices of this character as heretofore constructed, the contact point 20 was directly attached or operatively secured to the adjusting screw or regulator 24 thus also having 40 the screw or regulator electrically charged.

As these devices are manually operated and therefore held in the hand of the user—and as the control screw of necessity extends through the 45 end wall of the housing of the device to receive the finger control or knob 26,—the user was frequently subjected to dangerous shocks.

With my improved construction, all danger of such shocks is entirely eliminated because the 50 regulating or control screw is not electrically charged but has an insulated or non-conducting control contact with the electrically charged contact holding spring member 16, through the medium of the fiber or non-conducting stud 27.

55 In the constructions as heretofore employed, with the contact point directly secured to the bottom of the adjusting screw, it therefore rotated with the screw, and after use the contacts not only became worn by reason of the rotative movement of the upper contact point, but proper 60 adjustment and current flow were impossible because of the uneven wear resulting from the frictional rotative movement, thereby preventing a full face relation between the two contact points.

65 With my improved construction, this difficulty is eliminated and the upper contact point 20 is moved bodily toward the lower contact point 15, because the contact holding spring member 16 is supported at both ends by similar depending ends 18 of the spring member 16; the main central portion of the member 16 being forced downwardly by the insulator stud 27, causing the entire bottom end of point 20 to approach the lower contact point 15 and thereby provides a uniform

regulation of the current for the vacuum electrodes.

By forming the spring member 16 as shown, with both depending ends equal and secured in place, it is apparent that the upper contact point 5 is not made to move through the arc of a circle during its movement toward the lower contact point, but moves bodily in a vertical direction and hence presents its full face or lower end to the lower contact point 15.

10 With my improved construction, a uniform regulation of current is not only provided, but all danger of receiving an electric shock by the user while adjusting the regulating screw is impossible because the latter is fully insulated from 15 the electrically charged elements of the device; while at the same time a longer lived device is provided because the contact points are not subjected to the grinding or frictional wear encountered in the devices as heretofore made 20 wherein the upper contact point is carried by the adjusting screw and therefore is rotated on the upper face of the lower contact point 15.

25 In describing the particular embodiment of my invention, terms have been employed for purposes of description and not as terms of limitation, as modifications may be made without, however, departing from the spirit of my invention.

30 What I claim is:

1. In a device of the character described involving coils, a vibratory current interrupter comprising the combination of a pair of contact points; means whereby one of said points is yieldingly held in normal spaced relation with a terminal of one of the coils; means whereby the other contact point is yieldingly held spaced and in axial alignment with the first mentioned contact point and consisting of a leaf spring bent to provide a flat horizontally disposed portion, to 40 the underside whereof and intermediate of opposite ends said contact point is affixed, the ends of said spring being curved back beneath and substantially parallel with the contact point carrying portion while the immediate ends are then 45 bent downwardly into supporting legs disposed vertically between the vertical planes of the curved ends whereby the horizontally disposed contact holding portion is free to flex and move bodily; and a regulating member adjustably secured above said contact holding portion and provided at its lower end with a removable non-conducting stud adapted to engage the horizontally disposed portion of the leaf spring and thereby force said portion with its contact point 50 toward the first mentioned contact point.

2. In a device of the character described involving coils, a vibratory current interrupter comprising the combination of a pair of contact points; means whereby one of said points is yieldingly held in normal spaced relation with a terminal of one of the coils; a leaf spring having a flat horizontally disposed contact carrying portion, the ends of the spring being curved back beneath and thence downwardly into supporting 60 legs; and regulating means composed of an internally threaded sleeve, an adjusting screw disposed through said sleeve and having an axial bore, and a non-conducting stud removably secured in the bore at the end of the screw and 65 adapted to engage the horizontally disposed contact carrying portion.

70 WILLIS A. WHIPPLE.
